UNITED STATES PATENT OFFICE.

HARRY M. NACEY, OF CHICAGO, ILLINOIS.

FUSIBLE LINK.

Application filed May 9, 1919. Serial No. 296,036.

To all whom it may concern:

Be it known that I, HARRY M. NACEY, a citizen of the United States, and a resident of Chicago, in the county of Cook and State 5 of Illinois, have invented certain new and useful Improvements in Fusible Links, of which the following is a full, clear, and exact specification.

This invention relates to improvements in 10 fusible links adapted for use in connection with automatic heads for sprinkling systems and for fire-proof doors, shutters and windows for retaining them in their open position, in which heretofore a fulcrum block 15 has been enclosed by a chamber between and formed from the plates isolating the fulcrum block from the solder securing the plates together, the surfaces of which fulcrum block are parallel throughout and in 20 their operative position normally extend at an oblique angle with the plane of the surfaces of the plates with their flat longitudinal edges seated against the shoulders substantially parallel therewith, respectively 25 formed in the opposing plates.

These fulcrum blocks are intended to facilitate the separation of the plates on the melting of the solder, following the force of a pull or pushing-thrust, as may be, to 30 which the plates are subjected in their operative position. In practice it is found, however, that the plates do not separate with desirable quickness from either of these forces because of the pinching of the fulcrum block against its angular seats and the dragging friction between the plates; that a fusible link so constructed is substantially inoperative when, by accident or design, the space between the opposing surfaces 35 of the fulcrum block and the plates becomes filled with solder; that in the absence of the soldering the fulcrum block to both plates, following the common practice of sweating them together, the strength of adherence between the plates is insufficient for obtaining the best results.

The prime object of my invention, broadly stated, is to provide a fusible link with a fulcrum block, the construction of which 50 and its location between the plates of the link is such that on the melting of the solder the plates will have a rolling movement on the fulcrum block facilitating the separation of the plates, preventing a drag-

ging friction between the plates and the 55 fulcrum block from pinching against their seats, and a means by which it is possible and practical to solder the block to the plates and accordingly stiffen and strengthen the plates against accidental detachment. 60

More specifically stated, the object of my invention is a fusible link provided with a fulcrum block and opposing curved bearing surfaces, one of which surfaces is convex and the other concave with the fulcrum block and plates of the link so arranged with reference to each other that on the melting of the solder the plates are quickly laterally separated by a rolling frictional force, preventing the ends of the block impacting against and drag friction between the plates, and providing for soldering the plates to the surfaces of the block in their entirety, and accordingly increasing the extent of the soldered surfaces of the plates 75 and reducing the liability of the plates to accidental separation. 70

With these ends in view, my invention finds embodiment in certain features of novelty in the construction, combination and arrangement of parts by which the objects and certain other objects are attained, all as hereinafter fully described with reference to the accompanying drawings, and more particularly pointed out in the claims. 80

In said drawings:

Fig. 1 illustrates a longitudinal section taken on the line 1—1 of Figs. 10 and 11, a fusible link of the pushing-thrust type, in which my invention finds its embodiment. 90

Fig. 2 is a similar view taken on the same line of a modification.

Fig. 3 is a similar view taken on the same line of a further modification of the fusible link shown in Fig. 1. 95

Fig. 4 is a longitudinal sectional view taken on the lines 4—4 of Figs. 12 and 13 of a fusible link of the construction shown in Fig. 1 of the type which are pulled open.

Fig. 5 is a modification of the pull type 100 shown in Fig. 4 taken on the same line.

Fig. 6 is a similar view of a further modification taken on the same line as Figs. 4 and 5.

Fig. 7 illustrates in perspective the fulcrum block for the link shown in Figs. 1 105 and 4.

Fig. 8 is a similar view of the fulcrum

block for the links shown in Figs. 2 and 5.

Fig. 9 is a similar view of the fulcrum block shown in Figs. 3 and 6.

Figs. 10 and 11 are external plan views of the opposing plates for fusible links of the push-thrust type shown in Figs. 1, 2, and 3, and

Figs. 12 and 13 are similar views of the opposing plates shown in Figs. 4, 5 and 6.

10 All of the fusible links shown in Figs. 1, 2, 3, 10 and 11 are of the compression type, that is to say, their plates, 14 and 15, in their operative position are subjected to an endwise compressive force for effecting their separation on the melting of the solder normally securing them together, which plates are preferably provided toward one end with a recess, 16, for the reception of a curved depressed end portion, 17, opposed thereto, for aligning the opposite ends of the two plates so that the longitudinal stresses will not normally tend to separate the plates.

25 The plates, 14 and 15, are severally constructed from phosphorus bronze, brass or steel and, as shown in Figs. 1, 2 and 3, are provided with respective recesses, 18 and 19, forming a chamber in which is confined a rectangular fulcrum block, 20, which fulcrum block in Fig. 1 is provided transversely with opposing convex surfaces, 21, 21, adapted to fit in and against correspondingly concave bearing surfaces, 22, 22, in the plates, the upper and lower edges, 23, 23, of which blocks are opposed to but slightly separated from angular seats, 24, 24, formed in the plates and in slightly inclined parallel arrangement, so that on compressing the links following the melting of the solder the plates will have a rolling movement on the opposing convex surface of the fulcrum block for quickly forcing them apart and in the absence of the least amount of friction consistent therewith.

45 For example, the opposing convex surfaces for the fulcrum block may be limited in their location at the upper end of the fulcrum block, 25, 25, shown in the modification in Fig. 2 and opposed by concave bearing surfaces 26, 26, formed in the plates, but when so located the lower straight edge, 27, of the fulcrum block should be quite close to, if not seated against, the shoulder, 28, in the plate, 14, so that on the melting of the solder the plates will have a rolling movement in the absence of a dragging frictional resistance.

60 As a further modification, the fulcrum block, 20, in Fig. 3, is provided at both ends with convex curved surfaces, 29, 29, so that following the melting of the solder with the link under compression the plates are sep-

arated on the melting of the solder by a rolling movement on both ends of the fulcrum block for compelling the separation of the plates in the absence of dragging friction.

70 The fusible links shown in Figs. 4, 5, 6, 12 and 13 are of the pull type and for this purpose do not materially differ in their construction from what has been described other than that both plates are provided toward their extremities with openings, 30, for their connection with the struts of automatic sprinkler heads or with the chains for holding a fire-proof sash, door, et cetera, open, and wherein the link is subjected to a pull at both of its ends in opposite directions. Other than being of the tension type, the plates 31, 32, in Fig. 4 and the fulcrum block, 33, correspond with the construction and arrangement shown in Fig. 1.

75 In Fig. 5 the plates 34, 35, and the fulcrum block, 20, likewise correspond in construction and arrangement with the fusible link shown in Fig. 2, as does also the plates 36, 37, and the fulcrum block, 38, correspond in construction with the fusible link shown in Fig. 3, the fulcrum block in Figs. 1 and 4 being shown in perspective in Fig. 7, the fulcrum block in Figs. 2 and 5 being shown in perspective in Fig. 8, and the fulcrum block in Figs. 3 and 6 being shown in perspective in Fig. 9.

80 It is now to be observed that the fulcrum blocks and the chambers in which they are confined, shown in Figs. 1, 3, 4, and 6, are located in a plane at an oblique angle to the plane of the opposing surfaces of the plates between which they are confined; that in Figs. 2 and 5 the greater part of the fulcrum block lies in a plane parallel with the adjacent opposing surfaces of the plates, with the center from which the curved end is struck up located in the plane with that of the opposing flat surfaces of the plates; and that notwithstanding the differences 90 and location of the curved surfaces and their arrangement relative to the opposing plates between which they are confined, these several fulcrum blocks, in every instance, whether of the push or pull type, operate as curved cams opposed to concave bearing surfaces for forcing the plates apart by rolling action, as distinguished from a dragging friction for quickly forcing the separation of the plates before the solder has been melted to the thin consistency it heretofore required, and especially when the plates are subject to a dragging friction before separation.

95 In other words, the cam-like action, between the fulcrum block and plates of my invention, operates to positively force and direct the plates laterally away from each other, and in this connection it is important to observe that in the utilization of the 100

cam action for forcing the plates apart it is not only possible but practical to sweat the plates to and throughout the surfaces of the fulcrum block of my invention and 5 accordingly increase the strength and durability of a fusible link as a whole, and prevent the liability of the accidental detachment when both in and out of operative position.

10 Having thus described my invention, what I claim and desire to secure by Letters Patent is:

1. A fusible link, comprising in combination a pair of plate members, each provided with an elongated concave surface directly opposed to each other, and a fulcrum block provided with convex surfaces corresponding with and adjacently confined between said opposing concave surfaces.

20 2. A fusible link, comprising in combination a pair of plate members, provided with curved concave surfaces directly opposed to each other, and a fulcrum block provided with convex surfaces corresponding with 25 and adjacently opposed to said surfaces, which said block is located in a plane at an oblique angle to the plane of said plate members.

30 3. A fusible link, comprising in combination opposing flat plate members respectively provided with elongated concave surfaces directly opposed to each other, and an angular flat fulcrum block provided with convex surfaces conforming to and directly 35 opposing the concave surfaces in said plate members.

40 4. A fusible link, comprising in combination opposing flat plate members respectively provided with elongated concave surfaces directly opposing each other, and a flat angular fulcrum block, provided with convex surfaces conforming to and directly opposing the concave surfaces of the plate

members which said blocks extend obliquely to the plane of said plates.

45 5. A fusible link, comprising in combination flat angular plate members, respectively provided with directly opposing elongated curved surfaces, a fulcrum block provided with convex surfaces corresponding 50 with and located adjacent said concave surfaces, and a thin film of solder between and uniting said surfaces in their operative position.

55 6. A fusible link, comprising in combination flat plate members, respectively opposing each other, provided with elongated concave surfaces registering with each other, and a flat angular fulcrum block the opposite sides of which are each provided with a 60 convex surface respectively corresponding with and projecting into said concave surfaces, and a thin film of solder located between and uniting said surfaces in their operative position.

65 7. A fusible link, comprising in combination flat plate members, respectively opposing each other, provided with elongated concave surfaces registering with each other, a flat angular fulcrum block the opposite 70 sides of which are each provided with a convex surface respectively corresponding with and projecting into said concave surfaces, and a thin film of solder located between and uniting said surfaces in their operative 75 position, said fulcrum block being located to extend at an oblique angle to the plane of said plates.

In witness whereof, I have hereunto set my hand and affixed my seal, this 30th day 80 of April, A. D. 1919.

HARRY M. NACEY. [L.S.]
